METHOD OF AND MEANS FOR BALANCING ELECTRIC CIRCUITS

Filed Feb. 10, 1928

UNITED STATES PATENT OFFICE

CHARLES W. MCKIBBEN, OF HOUSTON, TEXAS, ASSIGNOR TO GULF OIL CORPORATION OF PENNSYLVANIA, OF PITTSBURGH, PENNSYLVANIA, A CORPORATION OF PENNSYLVANIA

METHOD OF AND MEANS FOR BALANCING ELECTRIC CIRCUITS

Application filed February 10, 1928. Serial No. 253,247.

The invention relates to the mode of procedure and the means for balancing the static and ohmic conditions of an operative circuit or line by use of a phantom circuit, and the 5 improved means for accomplishing this result.

Heretofore a resistance, as such, has been connected to the circuit to be balanced, in parallel therewith, and with a condenser of fixed 10 value. In some installations a retarding coil and a single condenser of fixed static capacity in series therewith has been connected to one terminal of the resistance body. The required effective resistance has been ascertained 15 by plugging in and out aliquot parts of the resistance in relatively large increments and decrements and the situation of the condenser has remained unchanged.

In other installations, it has been customary to first use a rheostat alone for the phantom circuit, which rheostat was always considerably out of balance and with which it was almost impossible to obtain a fine balance. Moreover, each conductor has its own rheostat plus a variable condenser, thereby necessitating the objectionable use of a plurality of rheostats. The static balance is effected by neutralizing the static discharge on long lines by means of a condenser and retarding 20 coil shunted around the entire rheostat or resistance and connected to the latter at a single point. My improved mode of procedure is to connect the resistance at various points to a plurality of condensers and to 25 shift the point of connection of each condenser over the resistance body to include a greater or less portion of the resistance of said body in shunt with the aforesaid condenser, and arranged so that the shifting operation cuts in and cuts out very small portions of said resistance in minute gradations 30 to render the adjustment more accurate and effective. In a refinement of the invention the condensers may have differing capacities.

The condenser used to shunt a larger part of the resistance may have the larger capacity and those which shunt smaller portions of the resistance should have correspondingly smaller capacities. All of the condensers, 35 however, should be adjustable with respect

to the various portions of the resistances operated upon and thus the resistance body is statically discharged at many points.

One of the objects of the invention is to improve and simplify the apparatus described 55 to the end that the result of its operation is more effective and the convenience of the structural arrangement contributes to its desirability.

Other and more specific objects, advantages, and benefits will readily appear to persons skilled in the art from a consideration of the following description and the accompanying drawings forming a part hereof 60 wherein:

Figure 1 is a top plan view of a rheostat by means of which my invention may be carried into effect and which embodies features of my invention.

Figure 2 is a side elevation thereof.

Figure 3 is an enlarged fragmentary view taken on line III—III of Figure 1.

Figure 4 is a similar view taken on line IV—IV of Figure 3.

Figure 5 is a diagram of circuits.

Figure 6 is a known means for varying the capacity of a condenser.

In all the views the same reference characters indicate similar parts.

The rheostat exemplified in the drawings 20 comprises a resistance body 10, which is shown as elongated and in cylindrical form. This particular resistance body consists of a supporting cylinder 11 of insulating material, or having an insulating face, upon which resisting wire 12 is wound in close tight convolutions. The wire is first, preferably, enameled so that the convolutions thereof may lie on the cylinder in actual contact. A tripod 13 forms a supporting base. The cylinder 11 is firmly mounted on this base. A 25 ring 14, of which there are two, one at each end of the cylinder 10, is frictionally held on the bare cylinder by clamping screws 15, and each ring 14 is provided with four laterally-projecting arms 16 for supporting the slide-supporting rods 17, respectively.

The rods 17 are all alike, and one is shown in detail in Figure 3. The rod 17 is preferably rectangular in cross section and has its 30

ends reduced in size, as at 18, for more conveniently insulating them from the arms 16. These reduced ends 18 are threaded for the clamping nuts 19. The upper ends 18 are 5 prolonged for a wire clamping nut to provide the terminal 20 for the rods. Each rod 17 has an electric terminal 20. A slide 21 is freely movable longitudinally of the rod and has an angular perforation to receive the rod to 10 prevent the slide from being rotated thereon.

A handle or thumb piece 22, of insulating material, such as hard rubber, a phenolic condensation product, fiber, or the like, is a means by which the slide may be moved vertically 15 on its rod. A contact spring-brush 23 is fixed to the slide 21, as shown in Figure 4, and has spring-pressure contact with the surface of the insulating body 10. The paths of the brushes 23 are cleaned of the insulating 20 covering to permit the brush 23 to make metallic contact with the surface of the wire covering 12. Another spring-brush 24 yieldingly connects the rod 17 and slide 21 to preserve intimate contact between these parts.

25 A ring 25 surrounds the wire 12 at the upper end of the cylinder and is clamped thereto by clamping screw 26. The ring 25 carries a binding post 27 which is the terminal for the upper end of the resistance body 11.

30 The lower ring 28 does not necessarily require a terminal post such as 27.

In Figure 5, I have shown a typical pole-changer arrangement, except that I have shown that either a battery 30, or in place 35 thereof two uni-directional dynamos, 31 and 32 may be employed as a source of continuous current, both of them are not required. The coils 33 are the pole-changer coils.

The relay 34 has two opposed coils 37 and 40 38 through which the current divides equally when conditions in the line circuit 35 are substantially balanced by the balancing circuit 36. All of this circuit arrangement is old and does not, per se, constitute my invention, 45 as so far described.

In Figure 5 the resistance body is shown as a coil, it could, however, be a stick or cylinder of resisting material, such for example as a rod of carbon or graphite composition, which 50 is an equivalent for the purpose intended.

The brush 23^a, which may be any one of the brushes of Figure 2, is connected by wire 37 to ground 38 and is adjustable vertically to include more or less resistance of wire 12 55 between terminal 27 and ground 38. By this means the included resistance of wire 12 is quickly and empirically determined.

Another brush, 23^b is connected to the free 60 terminal of condenser C and is adjustable vertically to include more or less of 12 between 23^a and 23^b.

Brush 23^c is connected to the free end of the condenser C' and is adjustable vertically to include more or less of resistance 12 between 65 23^a and 23^c.

Brush 23^d is connected to the free end of condenser C' and is adjustable vertically to include more or less of resistance 12 between 23^a and 23^d.

The capacity of condenser C is comparable in capacity to the extent of resistance shunted thereby. Condenser C' is of greater capacity and the resistance shunted thereby is also greater.

Condenser C² is of larger capacity than 75 either of its neighbors and it shunts practically all of resistance 12.

The exact value of resistance 12 shunted by the condensers may be ascertained by adjusted movement of the brushes 23 on the 80 resistance body 10.

The terminals 40 of the condensers are connected together and to the ground 38. The capacity of the respective condensers may also be varied to some extent by employment 85 of rotatable plates 40 with respect to associated fixed plates 41.

This arrangement is a refinement that may or may not be used.

The device is also advantageously susceptible of use in connection with means to eliminate static effect in a radio receiving set in which case the pole-changer and neutral relay may be dispensed with and in which 90 35 is the aerial.

While I have herein shown a single embodiment of my invention for a clear disclosure, it is manifest that changes may be made in the arrangement and procedure without departing from the spirit and scope of the appended claims.

Having described my invention, what I claim is:

1. An artificial line including a resistor conductively connected between a physical line and ground, means to adjust the effective series circuit resistance of the resistor to ground, and a plurality of condensers shunting portions of said resistor to ground, the condensers being of different capacities and the capacity of each condenser being substantially proportional to the resistance shunted by it.

2. The method of balancing the ohmic and static constants of a given physical line by establishing an adjustable artificial line which consists in conductively connecting a single resistor in series between said physical line and ground, adjusting the series circuit resistance of said resistor to ground, and shunting progressively decreasing portions of said resistor by condensers to ground, said condensers being of different capacities and the capacity of each condenser being substantially proportional to the resistance shunted by it.

3. The method of balancing the ohmic and capacity constants of a given physical line by establishing an adjustable artificial line which consists in conductively connecting a

5 resistor between the physical line and ground, adjusting the series circuit resistance of the resistor to ground, and connecting portions of said resistor to ground through condensers, said condensers being of different capacities, and the capacity of each condenser being substantially proportional to the resistance shunted by it.

10 4. An artificial line for balancing the ohmic and capacity constants of a given physical line, said artificial line including a resistor conductively connected between the physical line and ground, means to adjust the effective series circuit resistance of the resistor to ground, and a plurality of condensers shunting portions of the resistor to ground, the condensers being of different capacities, and the capacity of each condenser being substantially proportional to the voltage impressed upon its terminals.

15 In testimony whereof I have hereunto subscribed my name.

20 CHARLES W. McKIBBEN.
